Assignor to

P. J. Clark of said West Meriden.

Letters Patent No. 1111. Dated June 28, 1889.

The schedule referred to in these Letters Patent, and making part of the same.

To all whom it may concern:

Be it known that I, P. J. Clark, of West Meriden, in the County of New Haven, and State of Connecticut, have invented or produced a new and ornamental design for a Match Safe, and I, do hereby declare that the following is a full, clear and exact description of the same, reference being had to the annexed drawings, making a part of this Specification in which:

Similar letters of reference, indicate corresponding parts in the two figures.

This design consists in having the Match receptacles provided with bases in the form of a Scalloped Shell. A, represents a plate to which the Match receptacles B, are attached.

The receptacles B, are formed of two longitudinal halves of hollow cylinders or first turns of cones attached vertically to the plate A.

The tops of the receptacles are open to receive the matches and the lower ends have bases C, of the form of a Scallop shell made sufficiently convex to conform to the dimensions of the receptacles and fit snugly against the plate A, and form a neat and finished base or lower terminal, adding greatly to the appearance of the Match safe.

The bases C, it will be seen do not form a complete shell, the portion that adjoins the joint being removed so as to form a parallel edge a, at the junction of the receptacles and faces and thereby allow the other portion to be adapted to the receptacle and form a finished terminal.

I claim as new and desire to secure by Letters Patent.

The configuration of the bases or lower terminals C, the same being in the form of a Scallop Shell and constituting a new and ornamental device for a Match safe.
